H. J. FERRIS

PEDAL CAR

Filed Dec. 17, 1923

Inventor:
Howard J. Ferris,
By Dyerforth, Lee, Cutton & Miles,
Atkiss

UNITED STATES PATENT OFFICE.

HOWARD J. FERRIS, OF HARVARD, ILLINOIS, ASSIGNOR TO HUNT-HELM-FERRIS & COMPANY, OF HARVARD, ILLINOIS, A CORPORATION OF ILLINOIS.

PEDAL CAR.

Application filed December 17, 1923. Serial No. 681,122.

To all whom it may concern:

Be it known that I, HOWARD J. FERRIS, a citizen of the United States, residing at Harvard, in the county of McHenry and

5 State of Illinois, have invented a new and useful Improvement in Pedal Cars, of which the following is a specification.

This invention relates to toy wheel goods, particularly to pedal cars, play cars, and the 10 like, and is fully described in the following specification, as shown in the accompanying drawings; in which,

Fig. 1 is a side elevation of the front fork of a pedal car embodying the invention, 15 showing the near pedal crank removed;

Fig. 2 is a front elevation of the same;

Fig. 3 is a section on the line 3 of Fig. 1;

Fig. 4 is a detail of the crank; and

20 Fig. 5 is a detail of the end of the wheel shaft.

The embodiment illustrated comprises a front fork consisting of a U-shaped member 10 to which is secured a steering shaft 11.

25 Cup-like house members 12 are secured to the ends of the U-shaped member 10 by means of screws 13. These house members enclose a ball bearing 14 which fits over the reduced end 15 of the shaft. The center portion 16 of this shaft is enlarged and has a 30 shoulder 17 against which disks 18 may be drawn by nuts 19 which are screwed on the threaded portion 20 of the shaft. These disks have a relatively flat portion 21 near the rim which bear against each other, the

35 depth of the disks being such that the bearing portions 21 are in contact for about one-sixteenth of an inch, or such a matter, before the last disk 18 is drawn down against the shoulder 17. This provides a rigid wheel for 40 this purpose and one which, at the same time, can be readily disassembled to permit withdrawing or replacing the tire 22 which is held between the outwardly extending rim flanges 23.

45 The shaft 15 is drilled axially to permit of the insertion of the end 24 of the pedal crank 25. Ears 26 are preferably pressed up from opposite sides of the crank and lie within slots 27 in the reduced end 15 of the 50 shaft. A cotter-pin 28 passes through the

shaft and crank to retain the latter thereon, the entire torsion of the crank, however, being delivered to the shaft through the ears 26 and the slots 27.

When it is desired to use this vehicle as a 55 pedal car, the cranks are inserted, as shown in Fig. 2, but if it is desired to use it or sell it as a play car which is propelled by the child pushing with its feet on the ground while it rides the car, the cotter-pins 28 are 60 removed and the cranks withdrawn.

While I have shown and described certain embodiments of my invention, it is to be understood that it is capable of many modifications. Changes, therefore, in the construction and arrangement may be made 65 without departing from the spirit and scope of the invention as disclosed in the appended claims, in which it is my intention to claim all novelty inherent in my invention as 70 broadly as possible in view of the prior art.

I claim:

1. In toy wheel goods, a fork rotatably mounted for steering, bearings in the ends of said fork, a shaft journaled in said bearings, a wheel mounted on said shaft, axial holes in the ends of said shaft, cranks detachably secured in said holes and means for transmitting power from said cranks to said shaft independently of the securing 80 means.

2. In toy wheel goods, a fork rotatably mounted for steering, bearings in the ends of said fork, a shaft journaled in said bearings, a wheel mounted on said shaft, axial 85 holes in the ends of said shafts, cranks detachably secured in said holes, notches in the ends of said shaft, ears on said cranks for engaging said notches, and detachable means for retaining said cranks in said shaft. 90

3. In toy wheel goods, a fork rotatably mounted for steering, bearings, in the ends of said fork, a shaft journaled in said bearings, a wheel mounted on said shaft, axial holes in the ends of said shafts, cranks detachably secured in said holes, notches in the ends of said shaft, ears on said cranks for engaging said notches, and detachable pins passing through said cranks and shaft for retaining said cranks in said shaft. 95 100

4. In toy wheel goods, a fork rotatably mounted for steering, bearings in the ends of said fork, a shaft journalled in said bearings, a wheel mounted on said shaft, axial holes in the ends of said shaft, cranks detachably secured in said holes and means at the ends of said shaft for transmitting power from

said cranks to said shaft independently of the securing means.

In witness whereof I have hereunto set my hand and seal, this 14th day of December, 1923.

HOWARD J. FERRIS. [I. S.]
